UNITED STATES PATENT OFFICE

2,548,178

HOT METAL HANDLING APPARATUS

William S. Thompson, Watkins Glen, N. Y., assignor to Shepard Niles Crane & Hoist Corporation, Montour Falls, N. Y., a corporation of New York

Application June 25, 1948, Serial No. 35,081

5 Claims. (Cl. 212—131)

1
The general object of the present invention is to provide improved apparatus for handling hot metal. More specifically, the object of the invention is to provide improved means including a traveling hoist for moving molten metal held in a ladle from a charging station to a ladle discharging station or stations.

In the practice of the present invention a ladle containing molten metal is moved between a charging station and one or more discharging or pouring stations, by a traveling hoist which is supported by, and is movable along an elevated track or runway. Said hoist comprises hoisting mechanism including an electrical hoist motor for raising and lowering the ladle as may be required by differences in elevation of the charging and discharging stations, and to provide proper clearance between the ladle and objects beneath the track or runway along which the hoist is moved. The movement of the hoist along the supporting track and the operation of the hoisting mechanism is advantageously controlled from a cab unit which is supported by, and movable along the trackway, and which is provided with control mechanism through which the operator in the cab controls the movement of the cab and hoisting unit along the trackway, and controls the operation of the hoisting mechanism. Ordinarily, such cab and hoisting units are mechanically coupled so that a single propulsion motor, mounted either on the hoisting unit or on the cab unit, can be used to move the two units along the trackway. Usually however, the mechanically coupled units are each provided with at least one individual propulsion motor. The two mechanically connected units are also electrically connected to enable the operator in the cab to control the operation of the hoisting motor and to also control the operation of all propulsion motors included in the units.

To enable the operator in the cab to properly control the operation of the hoisting mechanism of the hoisting unit, it is practically essential that the operator's station in the cab should be in such close proximity to the ladle holding the molten metal that there is a substantial risk of serious injury to the operator in the cab as a result of the spilling of molten metal from the ladle when the cab and hoist units are mechanically coupled. The spilling of molten metal may be caused by faulty manipulation of the ladle in a charging or discharging operation, or may result from the fracture or burning out of the ladle.

The primary object of the present invention

2
is to provide apparatus for handling molten metal comprising cab and hoisting units, normally coupled mechanically and electrically, generally as above described, with simple and effective means through which whenever any dangerous spilling of molten metal from the ladle begins, the operator in the cab can disconnect the latter from the hoisting unit, and move the cab unit away from the hoisting unit with such rapidity as to eliminate, or to greatly minimize, the risk of serious injury to the cab and operator.

The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have illustrated and described a preferred embodiment of the invention.

Of the drawings:

Fig. 1 is an elevation of my improved apparatus for handling molten metal;

Fig. 2 is an end elevation of the apparatus shown in Fig. 1;

Fig. 3 is a plan view of means for electrically connecting and disconnecting the cab and hoist units which are shown on a smaller scale and with less detail in Fig. 1;

Fig. 4 is an elevation of means included in Fig. 1 for electrically connecting and disconnecting the cab and hoisting units shown in Fig. 1; and

Fig. 5 is a diagram illustrating the operation of the means for electrically and mechanically connecting the cab and hoisting units shown in Fig. 1.

In the drawings I have illustrated a preferred form of embodiment of the present invention which comprises a hoisting unit 1 and operator's cab unit 2, each supported by and movable along an elevated track 3. As is shown in Figs. 1 and 2, the track 3 is of a well known, monorail type, comprising a main I beam with its web vertically disposed, and two side by side flanged track or rails 4 and 5. The latter are secured to the main I beam at the opposite sides of its base flange. The hoisting unit 1 comprises a main frame suspended from the track rails 4 and 5 by trolleys 6 and 7 which are spaced apart in the direction of the length of the track 3, and also comprises a vertically movable, ladle supporting frame mounted in said main frame and supporting a ladle as hereinafter described. The cab unit 2 comprises a frame structure suspended from the

track rails 4 and 5 by trolleys 8 and 9. Each of the trolleys 6, 7, 8 and 9 comprises a pair of spaced apart wheels 10 in engagement with the upper edge or head of the track rails 4 and a second pair of wheels 10 in engagement with the upper edge or head of the track rail 5. As shown, the hoist unit trolley 6 supports a propulsion motor 11, and the cab unit trolley 8 supports a propulsion motor 12. Each of the propulsion motors 11 and 12 operates, when energized, to subject the wheels 10 of the corresponding trolley to a driving torque. The driving connections between the motors 11 and 12 and the corresponding trolley wheels 10 need not be illustrated or further described, inasmuch as they are of a well known type. As shown, neither the hoist unit trolley 7, nor the cab unit trolley 9 includes means for impressing a driving torque on their wheels 10.

Except for the means hereinafter described for mechanically and electrically connecting and disconnecting the two units, the hoist unit 1 may be, and as shown is of well known type, comprising a hoist motor 13 for raising and lowering a ladle 14 adapted to hold molten metal. The ladle 14 is directly supported by means of a bail-like part 15 having depending leg portions at opposite sides of, and pivotally connected to the ladle 14, and having a yoke portion suspended by hangers 16 carried by a vertically movable hoisting unit frame 17. The frame 17 is mounted for vertical movement in a guideway formed by vertically disposed I-beam portions 18 of the main frame of the hoisting unit 1. The frame 17 is supported and raised and lowered by means of a hoisting drum rotated by the customary hoisting motor 13 and cable connection between said drum and frame. The hoisting drum and cable connection are not shown, and need not be further described as they may be of well known type.

The cab 2 provides an operator's station including an operator's seat 19, motor control mechanism 20, a pedal 21 for controlling a foot actuated brake 22 for the trolley driving motor 12, and a hand lever 23 operating to interrupt the mechanical connection between the cab unit 2 and hoist unit 1, and to adjust a switch mechanism 24 to deenergize the trolley motor 11 when the hand lever 23 is turned out of its normal position. The trolley motor 11 for the unit 1 is provided with a so-called electric brake which may be of well known type and is automatically operated to prevent rotation of the shaft of the motor 11 when the normal energizing circuit for the latter is opened or deenergized. To enable the operator in the cab unit 2 to maintain the ladle 14 under close visual observation while at the same time shielding the operator from ladle heat radiation, the front wall of the operator's station or space in the cab unit 2 is advantageously closed by a plate 2A of glass or other transparent material adapted to withstand the effects of the heat radiation to said plate. The hoist motor 13 is also provided with an electric brake 26 for preventing rotation of the shaft of the motor 13 when the latter is deenergized.

As is shown in Figs. 1 and 5, the mechanical coupling between the units 1 and 2 comprises a tow bar 27. The latter has one end pivotally connected to the unit 1 at all times, and has its second end arranged to extend into a bell mouth opening in the adjacent end of a coupling member 28 which has its opposite end pivotally connected to the framework of the cab unit trolley

8. In the normal coupled condition of the two units, a plug or coupling body 29 extends through apertures in the top and bottom walls of the member 28 and through the then registering aperture 27' in the end of the tow bar 27 then extending into said member 28. The body 29 is pivotally connected to a crank arm 30 mounted to turn about a supporting pivot 31. A crank arm 32, rigidly connected to the crank arm 30, has its free end connected by a link 33 to the arm 34 of the lever 23. The later is mounted to turn about a pivot or shaft 35, and is rigidly connected to a lever arm 36 which turns with the lever 23 about the shaft 35.

The lever arm 36 is connected by a link 37 to one arm of a switch adjusting bell crank lever 38 mounted on a pivot 39. As diagrammatically shown in Fig. 5, the second arm of the lever 38 is connected to the operating rod or stem 40a of the switch 24, and the stem 40a is connected to each of a plurality of switch members 40 of the bridging contact type which are shown as parallel to one another. When the lever 23 is turned counterclockwise from its positoin shown in Fig. 1 into its position shown in Fig. 5, the plug 29 is moved down out of the tow bar aperture 27', and the units 1 and 2 are thus mechanically disconnected. The counterclockwise movement of the lever 23 also moves the upper end of the bell crank lever 38 into the position in which it engages and is held against return movement by a latching detent 41. As diagrammatically shown in Fig. 5, the detent 41 is pivotally supported by a pivot pin 42, and a stop pin 43 normally holds the latch arm in position to be engaged by, and moved into locking engagement with the lever 38, following the engagement of the latter with the bevelled end 44 of the latching detent 41, as the lever 23 is turned from its position shown in Fig. 1 into its position shown in Fig. 5.

When the lever 23 is in the position shown in Fig. 5, and the control mechanism 20 is adjusted to energize the motor 12 for such movement, the cab unit 2 moves rapidly to the left, from the hoisting unit 1. The latter is then held stationary by the electric brake 26, which is then in the condition in which it prevents rotation of the trolley motor 11, as a result of the deenergization of the motor 11 by the adjustment of the switch 24 into its condition shown in Fig. 5.

The control of the hoist motors by the mechanism 20 is effected through conductors included in one or more cables 45 normally forming an electrical connection between the units 1 and 2. The movement of the cab unit 2 away from the hoisting unit 1 separates the sections 46 and 47 of an automatic disconnect box, and thereby opens the previously closed energizing conductor connections between the mechanism 20 and the motors 11 and 13. As shown, there are two cables 45, each having one end connected to the box section 47 and having its other end connected to the cab unit 2. In their normal positions, the box sections 46 and 47 have their lower ends hinge connected by means of bracket parts 48 secured to the underside of the section 46, and a bottom lip or flange portion 49 of the box section 47. Said flange portion 49 then serves, in effect, as a pintle received in a concave recess formed in the upper side of each bracket 48.

As shown, the disconnect box section 46 is rigidly connected to the frame of the hoist unit 1. In the normal operative condition of the apparatus, shown in Figs. 3 and 4, the disconnect box

section 47 is held against the section 46 by locking means comprising two locking hook or bar members 50 and cooperating latch members 55. The two locking bar members 50 are normally parallel to one another and to the direction of movement along the track rails 4 and 5 of the hoisting unit, and are at opposite sides of the sections 46 and 47. Each locking bar extends loosely through the flange portion 51 of a corresponding bracket member secured to the section 46. A spring 52 acting between the flange 51 and an abutment member 53 secured to the end of the locking bar 50 adjacent the hoisting unit, tends to move the enlarged opposite end portion 54 of the bar 50 to the right from its position shown in Figs. 3 and 4. Such movement of each locking bar 50 is prevented, in the normal condition of the apparatus, by the corresponding latch member 55. Each member 55 is pivotally supported by a pivot 56 carried by the box section 47. In its position shown in Figs. 3 and 4, bifurcated end portions of each latching member 55 straddle the body portion of the adjacent bar 50 and are engaged by the enlarged end portion 54 of said adjacent bar. In consequence, the aggregate tension force of the two springs 52 then collectively holds the disconnect box section 47 in snug contact with the box section 46.

In the normal operative condition of the apparatus, each latch member 55 is held in its latching position shown in Figs. 3 and 4, by a corresponding locking lever 57 which is pivotally connected to the box section 47 by a corresponding pivot 58. The levers 57 are bell crank levers and are so arranged that when in their locking position, shown in Fig. 3, the tension of the springs 52 act through the latch members 55 against the short engaging arms of the levers 57 in the direction to hold the long arms of the levers against the box section 47 and thereby maintain each of the short lever arms in engagement with the corresponding latch member. The long arms of the levers 57 are each connected by a common clevis 59a to one end of a flexible connecting element 59 which, as shown, is a chain. The second end of the chain 59 is anchored to the framework of the cab unit 2. When the tow bar 27 is disconnected from the cab unit 2 and the latter is moved away from the hoisting unit 1, the chain 59 moves each bell crank lever 57 into a position in which its short arm disengages the corresponding latching member 55. This permits the latter to turn about its supporting pivot 56, under the action of the springs 52, into a position in which it no longer cooperates with the corresponding locking bar 50 to hold the disconnect box sections 46 and 47 in contact with one another. As the movement of the cab unit 2 continues, the section 47 is separated from the section 46 and thereafter shares the bodily movement of said unit.

Mounted in the section 46 are a plurality of laterally displaced contact members 61, which are parallel to one another and to the direction of movement of the units along the track rail 3. As is made apparent in Fig. 4, each contact 61 has a cylindrical end portion axially movable in a corresponding socket member 61' anchored in the disconnect box section 46. A spring 63 in each socket surrounds a portion of the corresponding contact member which is smaller in diameter than said cylindrical end portion, and acts between the closed end of the latter and said enlarged end portion of the contact 61. When the disconnect box sections 46 and 47 are in en-

gagement, as shown in Fig. 4, each of the contacts 61 is in axial alignment and in abutting engagement with a corresponding contact 64 carried by a support 65. The latter is within, and rigidly connected to the box section 47. When the contacts 61 and 64 are in such engagement, the springs 63 are compressed and under sufficient tension to maintain a desired contact pressure between each contact 61 and the abutting contact 64.

As diagrammatically shown in Fig. 5, the uppermost contact 61 is connected by a conductor 66 to a brush engaging the commutator 68 of the trolley motor 11, while the second brush engaging the commutator 68 is connected by a conductor 67 to the contact 61 immediately beneath the contact 61 connected to the conductor 66. The two lower contacts 61 are connected to one another through conductors 69 and 70 which are connected in series with one another and with the field winding 71 of the motor 11, and with the relay winding 72 through which the application of the so-called electric brake 25 to the shaft of the motor 11 is controlled. The brake 25 may be, and ordinarily is of the well known type comprising a brake member spring biased for movement into braking engagement with the shaft of the motor 11, but which is held out of such engagement by the relay winding 72 when the latter is energized.

As shown in Fig. 5, the contacts 61 connected to the conductors 66, 67, 69 and 70 engage contacts 64 connected to conductors 73, 74, 75 and 76, respectively. Each of the conductors 73, 74, 75 and 76 is connected to a corresponding contact 40b of the switch 24. When the switch lever 38 is turned clockwise from the position in which it is shown in Fig. 5 into its normal position, the switch members 40 are moved into position in which they connect the conductors 73, 74, 75 and 76 to conductors 78, 79, 80 and 81, respectively. The last mentioned conductors are individually connected to corresponding contacts 40c of the switch 24, and may be connected to the control mechanism 20 in the cab unit 2, for actuation of the motor 11 in accordance with the adjustment of said mechanism.

With the hoist and cab units 1 and 2 respectively coupled mechanically and electrically, as shown in Fig. 1, the control mechanism 20 in the cab unit 2 is adapted to simultaneously energize both trolley motors 11 and 12 for simultaneous operation as required to move both the units 1 and 2 along the supporting track 3 in either direction, and to operate the hoisting motor 13 as required to raise or lower the ladle 14 as conditions make desirable. However, when as a result of ladle fracture or other cause, molten metal spills out of the ladle 14 and thus subjects the operator to risk of serious injury by the hot metal or its heating effects which would exist if the cab unit 2 were maintained in its normal position relative to the hoisting unit, the operator may rapidly move the cab and himself to a position safely displaced from the hoisting unit 1 by turning the lever 23 counterclockwise, as seen in Fig. 1, and by simultaneously adjusting the control mechanism 20, if necessary, to effect a rapid movement of the cab unit 2 away from the hoisting unit 1. Such rapid movement of the cab unit 2 away from the associated hoisting unit 1 will ordinarily prevent serious injury to the cab unit or to the operator, by the molten metal spilled from the ladle 14.

The counter-clockwise movement of the lever

23 actuates the switch 24 to deenergize the propulsion motor 11 mounted on the hoisting unit 1, and thus insures the immediate braking action of the electric brake 25, and the maintenance of the unit 1 in the position which the unit then occupies. Following a short initial movement of the cab unit 2 away from the hoisting unit 1, the chain 59 tilts the levers 57 and thus interrupts the normal locking connections between the box sections 46 and 47 provided by the locking bars 50 and latching members 55. As the movement of the cab unit 2 away from the hoisting unit continues, the lip 49 of the box section 47 is pulled out of engagement with the recessed bracket 48 carried by the box section 46, and the box section 47 is then supported by the chain 59.

In Fig. 5 only conductors and contacts for controlling the operation of the motor 11 are shown. For the control of the motor 13, the contacts 61 and 64 in the box sections 46 and 47, respectively, and the contacts 40 of the switch 24, and the conductors associated with said contacts, may be duplicated. The duplicate control contacts 61' and 64' for the motor 13 are shown in Fig. 3, but the illustration in Fig. 5 of the associated switch contacts, conductors and windings seems unnecessary. The casing extension 83 of the cab unit 2 is adapted to serve as a housing for resistance elements utilized in the control of the motors 11, 12 and 13.

While in accordance with the provisions of the statutes, I have illustrated and described the best form of embodiment of my invention now known to me, it will be apparent to those skilled in the art that changes may be made in the form of the apparatus disclosed without departing from the spirit of my invention, as set forth in the appended claims, and that in some cases certain features of my invention may be used to advantage without a corresponding use of other features.

Having now described my invention, what I claim as new and desire to secure by Letters Patent, is:

1. Apparatus for handling hot metal, comprising in combination an elevated track, a traveling hoist unit supported by and movable along said track, a molten metal container carried by said hoist unit, an operator's cab unit supported by and movable along said track, a propulsion motor mounted on said cab unit, a motor mounted on said hoist unit, a towing connection between the two units including coupling parts readily adjustable to open and close said connection, motor control mechanism on said cab unit, a control connection between the two units including circuit making and breaking parts readily adjustable to open and close the lastmentioned connection through which the hoisting unit motor may be controlled by said control mechanism, and means on said cab unit operatively connected to said coupling and circuit making and breaking parts for opening said towing and control connections to permit the rapid separation of said units.

2. Apparatus for handling hot metal, comprising in combination an elevated track, a traveling hoist unit supported on and movable along

5 said track, a molten metal container unit carried by said hoist, an operator's cab unit supported by and movable along said track, a propulsion motor mounted on said cab unit, a second propulsion motor mounted on said hoist unit, a towing connection between the two units including coupling parts readily adjustable to open and close said connection, motor control mechanism on said cab unit, a control connection between 10 the two units including circuit making and breaking parts readily adjustable to open and close the last mentioned connection through which said second propulsion motor may be energized by said control mechanism, normally inoperative braking mechanism on said hoisting unit adapted when operative to prevent movement of the hoisting unit along said track, and means on said cab operatively connected to said coupling and circuit making and breaking parts operable to open said towing and control connections and render said braking mechanism operable.

25 3. Apparatus as specified in claim 1, in which said control connection comprises coupling contacts mounted on said hoist unit, cooperating contacts, means for detachably holding each of said cooperating contacts to said hoist unit in engagement with a corresponding coupling contact, and a mechanical connection between cooperating contacts and said cab unit through which the latter moves said cooperating contacts out of engagement with said coupling contacts on movement of the cab unit away from the hoist unit.

30 4. Apparatus as specified in claim 1, in which said control connection comprises coupling contacts mounted on said hoist unit, a contact support, cooperating contacts mounted on said support, means for detachably connecting said support to said hoist unit with each of said cooperating contacts in engagement with a corresponding coupling contact, locking mechanism including lever means connected to said support for adjustment relative to the latter between a normal locking condition and an unlocking condition, and a mechanical connection between said lever means and said cab unit through which the latter adjusts said lever means into its unlocking position on movement of the cab unit away from the hoist unit.

35 5. Apparatus as specified in claim 1, in which the means on the cab unit for opening the towing and control connections comprises an adjustable element of the towing connection, a switch element of the control connection and a lever adjustable by an operator in the cab unit and a link connection between the lever and each of said elements.
